UNITED STATES PATENT OFFICE.

JAMES H. LYNCH, OF BELLE VERNON, PENNSYLVANIA, ASSIGNOR OF FOUR-TENTHS TO FRANK G. MYERS AND ONE-TENTH TO THOMAS E. CUNNINGHAM, OF PITTSBURG, PENNSYLVANIA.

RAILROAD TIE AND FASTENER.

No. 874,609.

Specification of Letters Patent.

Patented Dec. 24, 1907.

Application filed May 6, 1907. Serial No. 371,987.

To all whom it may concern:

Be it known that I, JAMES H. LYNCH, a resident of Belle Vernon, in the county of Fayette and State of Pennsylvania, have invented a new and useful Improvement in Railroad Ties and Fasteners; and I do hereby declare the following to be a full, clear, and exact description thereof.

My invention relates to railroad ties and fasteners, and has for its object to provide a cheap, simple and efficient form of a tie and fastener for railroad rails which will firmly and securely hold the rails in place and in line and thereby overcoming the possibility of the loosening, spreading or side movement of the rails.

My invention consists, generally stated, in the novel arrangement, construction and combination of parts as hereinafter more specifically set forth and described and particularly pointed out in the claims.

To enable others skilled in the art to which my invention appertains to construct and use my improved tie and fastener, I will describe the same more fully, referring to the accompanying drawings, in which—

Figure 1 is a side elevation of my improved tie and fastener. Fig. 2 is a plan view of the same. Fig. 3 is a longitudinal central section of the tie and fastener. Fig. 4 is a cross-section of two ties on the line 4—4 Fig. 2 and looking in the direction of the arrows. Figs. 5 and 6 are perspective views of the two clamping pieces or tie plates for the rail. Fig. 7 is a like view of the lining plate for the rail between the ties. Fig. 8 is a like view of the wedge or key for the tie plates. Fig. 9 is a cross-section of the tie showing a modification for holding the key in place. Fig. 10 is a perspective view of the key shown in Fig. 9.

Like symbols of reference herein indicate like parts in each of the figures of the drawings.

As illustrated in said drawings, 1 represents my improved tie which is of hollow rectangular shape in cross section and formed of metal either by casting or by rolling. Extending out from each side of the tie 1 are the upper and lower flanges 2 and 3 which form the recess 4 between them and throughout the length of the tie, while the rails A are adapted to rest upon the upper face a on said tie and be held in place in the following manner. On one side of each tie 1 is the inner clamping portion 5 which is integral with

said tie and is provided with the overhanging inner face 6 for fitting over and engaging with the inner base flanges b of one of the rails. On the other end of the tie 1 is the inner clamping portion 7 which is removably held on said tie and other rail A by means of the downwardly projecting sides 8 thereon for fitting along the sides of the tie and provided with guides or grooves 9 therein for the purpose as hereinafter described. The portion 7 is also provided with the downwardly depending portion 10 in the center thereof for passing through a hole 11 in the top face a on the tie and into the interior of said tie for holding said portion in place and this portion can be further secured and clamped to said tie if desired by a wedge or key 12 passing through a slot 13 in said depending portion 10 and engaging with the under side of said upper face a. The clamping portion 7 is provided with the overhanging inner face 14 for fitting over and engaging with the inner base flange b on the rail.

Fitting against the rails A and on the outer side of the same are the movable clamping portions 15 which fit over the ends of each of the ties 1 and are adapted to slide thereon through the downwardly projecting sides 16 thereon fitting around the upper flanges 2 on said ties through a groove 17 in said sides. The portions 15 have an overhanging inner face 18 thereon for fitting over and engaging with the outer base flange c on the rails and said portions are also provided with the guiding arms 19 extending inwardly from the sides 16 for fitting within the recesses 4 in the sides of the tie 1 and within the grooves 9 in the sides 8 of the clamping portions 9.

Extending down through an opening 20 in the top face a of the tie 1 is a key 21 which is provided with a wedge face 22 on its inner face for engaging with a slot 23 formed in the side of said opening and with the outer face of the movable clamping portion 15 for holding the same in place, and if desired, the key can be provided with a groove 24 in its upper face for the reception of a wire 25 which has its ends 26 passed through holes in the upper flanges 2 of said tie and bent under said flange in the recess 4 to further assist in holding the portions 15 in place, as shown in Figs. 9 and 10.

Extending between two ties 1 and on the inner side of each of the rails A is the liner plate 27 which is set vertically between said

ties and preferably extends below said ties, while it is also provided with the overhanging inner side edge 28 for fitting over and engaging with the inner base flange *a* of said rails. The end faces 29 on the plate 27 are adapted to fit within seats 30 on the clamping portions 5 and against the upper flanges 2 and on the lower flanges 3 of the ties 1 on one side and within seats 31 on the sides 8 on the clamping portions 7 and the lower tie flange 3 on the other side, while a slot 32 is formed in said end faces 29 for fitting around the guiding arms 19 on the slideable clamping portions 15 to assist in guiding said arms and portions 15 and to permit the insertion and withdrawal of the clamping portions and liners.

The use and manner of assembling my improved tie and fastener is as follows—When the ties 1 are placed in position, as shown in Fig. 1, the movable clamping portions 7 are then placed in position on said ties by inserting the depending portions 10 therein through the hole 11 in the top *a* of the ties 1 and placing the keys 12 within the same, and after which the liner plates 27 are inserted in place within said ties and portions 5 and 7 through the seats 30 and 31 in said portions 5 and 7. After this is accomplished the slideable clamping portions 15 are placed in position on said ties 1 with their arms 19 fitting within the recesses 4 in said ties and within the grooves 9 and seats or slots 32 in the plates 27 respectively, so that the rails A can then be clamped within said clamping portions 5, 7 and 15 by said portions 15 by drawing them up to position through the placing of the keys 21 in the openings 20 on the face *a* of the ties and forcing them down in said openings against the ends of said portions 15 by their wedge faces 22.

When it is desired to remove the parts of my improved tie and fastener for any purpose, the wedges or keys 21 are removed from the openings 20 in the tie faces *a*, when the clamping portions 15 can then be slid along or removed from the ties 1, and after this is done, the liner plates 27 are removed from the clamping portions 5 and 7, so that the latter can be removed from the ties through the withdrawal of the keys 12 and leave the rails A free to be moved or replaced, as desired.

It will thus be seen that my improved rail-road tie and fastener will do away with the use of bolts and spikes so commonly employed in these devices, while at the same time when in use the rails will be clamped tightly and be prevented from movement or displacement at any time. The parts can be conveniently and rapidly set in position and will hold the rails in perfect alignment at all times, while such parts can be easily and durably made by casting and rolling and will not require any skilled labor in the handling

or setting of the same in place. The ties and liner can be easily and thoroughly clamped and if desired used with concrete around the same and within the ties.

Various modifications and changes in the design and construction of my improved tie and fastener may be resorted to without departing from the spirit of the invention or sacrificing any of its advantages.

What I claim as my invention and desire to secure by Letters Patent is—

1. A tie and fastener for rails comprising a tie having a flange extending out from the sides of the same, a removable clamping portion on said tie for engaging with one side of said rail, a slideable clamping portion on said tie and fitting around said flanges for engaging with the other side of said rail, means for holding said slideable portion in place, and guides or arms on said slideable portion for fitting under said flanges and within said removable clamping portion.

2. A tie and fastener for rails comprising a tie having a flange extending out from the sides of the same, a removable clamping portion on said tie for engaging with one side of the rails and having downwardly projecting sides thereon, a slideable clamping portion on said tie for engaging with the other side of said rail and fitting around said flanges by downwardly projecting sides thereon, means for holding said slideable portion in place, and guides or arms on the sides of said slideable portion for fitting under said flanges and within the sides on said removable portions.

3. A tie and fastener for rails comprising ties, clamping portions for the rails on said ties, and a liner plate fitting between said ties and within the said clamping portions for engaging with the rail.

4. A tie and fastener for rails comprising ties, clamping portions for the rails on said ties, a liner plate fitting between said ties and within said clamping portions, and slideable clamping portions on said ties and engaging with said liner plate.

5. A tie and fastener for rails comprising ties, clamping portions for the rails on said ties, a liner-plate fitting between said ties and within said clamping portions, and slideable clamping portions on said ties having guides or arms engaging with said liner plate.

6. A tie and fastener for rails comprising ties, clamping portions for the rails on said ties, a liner plate having a seat thereon fitting between said ties and within said clamping portions, and slideable clamping portions on said ties having guides or arms thereon engaging with the seat in said liner plate.

In testimony whereof, I, the said JAMES H. LYNCH have hereunto set my hand.

JAMES H. LYNCH.
